PUMP AND MOTOR STRUCTURE

Sven T. Nelson, Michigan City, Ind.

Application May 28, 1932, Serial No. 614,082

16 Claims. (Cl. 230—194)

The invention relates to pump and motor structures such as elastic fluid compressors and engines. The principal object of the invention is to provide an improved construction by which the capacity or power and the piston displacement can be greatly increased without correspondingly increasing the size and weight or, in other words, to provide a construction in which the size and weight per unit of capacity is materially decreased as compared with compressors and engines now in use. Further objects of the invention are to provide an improved compressor or engine of large capacity or power for given size and weight and of the multiple piston radial type, that is in which the pistons and piston chambers are radially disposed about a crank-shaft, and particularly to provide an improved air or gas compressor of this type.

With these and other objects in view, the invention consists in the features hereinafter set forth and more particularly pointed out in the appended claims.

In the drawings, which illustrate an air or gas compressor embodying the invention:—

Fig. 1 is a view in vertical cross section on the line 1—1 of Fig. 2.

Fig. 2 is a vertical longitudinal section on the line 2—2 of Fig. 1.

Figs. 3 and 4 are detail views illustrating the piston packing.

Figs. 5 and 6 are enlarged detail views of the air inlet and outlet valves for the compressor.

In accordance with the present invention, the pistons and the cylinders, or, more properly speaking, the piston chambers, are radially disposed with reference to the crankshaft, have rectangular cross sections which are relatively long and narrow with the sectional lengths disposed parallel to or extending lengthwise of the crank-shaft and the narrow sectional widths transversely thereof, and the shaft is preferably provided with multiple cranks to which each of the pistons is connected.

In the preferred construction, as shown, the casing comprises three main sections, an intermediate body section or cylinder block 10 and oppositely disposed heads 11 abutting against the opposite end faces of the body section and suitably bolted thereto, each section being formed of a single integral casting. The intermediate body section is substantially cylindrical, is provided with a supporting base 12 and with inner partition walls forming a central crank chamber 13 and a series, five in number in the form shown, of radial piston chambers 14 which open at their inner ends into the crank chamber and extend to the end faces of the body section, being closed at their ends by the heads 11. The piston chambers thus formed by the flat partition walls 15 of the body section and the end heads 11 are

materially elongated in a direction lengthwise of the shaft and contracted transversely thereof. That is to say, the piston chambers have sections in the form of long narrow rectangles, the lengths of which extend parallel to the shaft or in axial direction, and the relatively narrow widths extend transversely of the shaft or in a circumferential direction. Preferably the lengths of the sections of the piston chambers are several times the widths. For example, in the form shown, the length of each piston chamber is four times that of its width.

The chambers 16 intermediate the piston chambers and bounded by the walls 15 and circumferentially extending inner and outer walls 15 17 and 18 form jacketing spaces which, in the form shown, are closed at their ends by the end walls 19 (see Fig. 2). Preferably also, the walls 15, 17 and 18 are provided with stiffening ribs or partitions 20 within the chambers 16 which, together with the end walls 19, aid in bracing the long flat side walls 15 of the piston chambers.

The circumferentially extending wall 18 and the outer peripheral wall 21 of the body section 10 are connected by end and intermediate partition walls 22 and 23 (see Fig. 2) and by substantially radial partition walls 24 (see Fig. 1), and these walls, in the form shown, form inlet and outlet valve chambers 25 and 26, a single inlet and a single outlet chamber being provided for each piston chamber. Preferably, the walls 24 are provided with openings 27 so that annular inlet and outlet manifolds are formed connecting the corresponding valve chambers and communicating respectively with main inlets and outlets 28 and 29 formed in the upper portion of the body section 10.

The abutting faces of the body section 10 and the ends or heads 11 are machined to form tight joints, and the heads are preferably provided with jacketing portions 30 and are also provided with suitable bearings 31 for the crankshaft. The latter, in the form shown, is formed of two end sections 32 and an intermediate section 33. The end sections are provided on their inner ends with integral crank arms or cheeks 34 having integral crank pins 35. The intermediate section comprises crank arms 36 and an integral offset counterweighting portion 37. The cheeks 34 or crank arms 36 are recessed to provide sockets 37 for receiving the inner ends of the crank pins and large bolts 38 extending through the crank arms and pins securely connect the three sections of the shaft. To prevent torsional stresses from loosening the connections between the crank pin sections, the bolts 38 extend eccentrically through the crank pins.

Each of the elongated rectangular pistons 39 is connected by two connecting rods or pitmans to the two crank pins of the shaft, all of the

pitman rods associated with each pin being arranged in the same plane. One of the connecting rods 40 of each set is rigid or is formed integral with an eccentric strap or ring 41 journaled on the crank pin between the cheeks and the other connecting rods 42 of the set have their inner ends extending within a groove in the ring 41 and pivotally connected thereto by pins 43. Lubricating ducts 44 extend through the shaft sections and crank pins 35 and in line with a pipe 45 which extends between the crank arms 36 of the intermediate shaft section, and these ducts communicate with the shaft bearings 31 and with the crank pin bearings. If desired these bearings can be readily provided with anti-friction rollers.

Preferably both the contacting walls of the elongated rectangular pistons and piston chambers are provided with grooves for receiving spring-pressed metal packing strips. As shown, the grooves are formed in the end and side walls of each piston and spring-pressed straight and angular or corner packing strips 46 and 47 are arranged therein, and are provided with overlapping ends as indicated in Figs. 3 and 4. These packing strips and grooves are arranged near the outer end of the pistons and at their inner ends the flat side walls 15 of the piston chambers and the end walls thereof formed by the heads 11 are provided with grooves for receiving spring-pressed metal packing strips 48 and 49. Preferably, for convenience in manufacture, the packing strips 49 and the grooves formed in the heads 11 are circular and each of the packing strips 48 is formed of two sections having overlapping ends and pressed apart in longitudinal direction by a spring 50, as shown in Fig. 2. By providing both pistons and the walls of the piston chambers with packing strips, tight joints are assured.

Each piston comprises an outer end wall or head 51 of elongated rectangular form, and a skirt comprising side and end walls 52 and 53, an intermediate stiffening wall 54 parallel with the side walls 52 and a transverse stiffening partition 55. The intermediate partition is provided with enlarged portions 56 for receiving the pin 57 by which the piston is connected to the pitmans 40 and 42, and this stiffening partition 54 and the stiffening partition 55 are cut away to receive and permit the relative movement of the pitmans.

The construction is of adequate strength and tight joints can be formed between the pistons and walls of the piston chambers, notwithstanding their elongated rectangular section. Also, the series of radial rectangular pistons and piston chambers provides a structure in which the size and weight per unit of capacity or power is very materially decreased, or in other words, for a given size and weight, the capacity or piston displacement is very materially increased. Thus it is estimated that the particular structure shown need not be materially greater in size and weight than a five cylinder radial compressor or engine, but would have nearly four times the piston displacement. Furthermore, either for a compressor or an engine the valve arrangement would be materially simplified for the same capacity.

In the construction illustrated, compressor inlet and outlet valves are shown and are carried by suitable valve seats mounted on the flattened portion of the partition wall 18 at the outer ends of the piston chambers, sufficient space be-

ing provided for a large inlet and a large outlet valve for each piston chamber. The inlet valve seat 58 is circular in section and rests upon a circular shoulder or rabbet 59 formed in the wall 18. A thin metal valve disk 60 held in place by a spring disk 61 normally closes the ports 62 in the valve seat, these parts being guided on a hub portion 63 of the valve seat. A bolt 64 having a nut 65 on its outer end, threaded centrally through the valve seat, holds a resilient abutment consisting of a plate 66 and washers 67 in position and which cushion the opening movement of the inlet valve. A bolt 68 threaded into the outer wall 21 of the main body of the casing engages the outer end of the bolt 64 and removably holds the valve seat and valve in position.

The outlet valve is of somewhat similar construction. It comprises a valve seat 69 seated in a rabbet 70 and similar valves, valve springs 20 and cushioning abutment plate and washers, these parts being mounted on the hub portion 71 of the valve seat and held in place by nuts 72 threaded on the hub. A bolt 73 having a head 74 thereon is threaded through the hub 25 of the valve seat and engages an offset on the casing wall 21 and removably holds the outlet valve and valve seat in position.

The outer end walls of the valve chambers and corresponding portions of the heads 11 of the casing are provided with openings of sufficient size to permit the insertion and removal of the valves and these openings are normally closed by removable cover plates 75. It is also noted that the ends or heads 11 are provided with openings 76 35 extending therethrough which open into the crank chamber and these openings are normally closed by cover plates 77. Suitable inlet and outlet ports, not shown, may be provided for circulating medium through the jacketing spaces 40 16 and 30.

The body section 10 is provided at the lower portion of the crank chamber 13 with a trough-like portion 79 for the collection of lubricant. The portions of the end faces of the body section 45 between the piston chambers are grooved, as at 80, so that the spring-pressed packing strips or rings 49 can snugly engage the narrow end walls 53 of the pistons.

While the particular construction shown is 50 adapted and intended as an air or gas compressor, it is obvious that suitable valves and ignition mechanism could be provided to adapt the construction for use as an internal combustion engine which is either air or water cooled. If air 55 cooled, the spaces between the radial cylinders could be left open for circulation of air therethrough. Other changes may be made in the details set forth without departure from the scope 60 of the invention as defined in the claims.

I claim as my invention:

1. In an elastic fluid pump or motor structure, a frame or casing having a crank chamber, a crankshaft extending therethrough, the casing having a series of relatively fixed radial piston chambers of elongated, substantially rectangular section with their relatively long side walls extending lengthwise of said shaft, an inlet and an outlet valve at the outer end of each of said chambers, pistons in said chambers and connecting rods coupling the piston to a common crank or cranks of said shaft.

2. An elastic fluid pump or motor structure comprising a frame or casing, a crankshaft journaled therein, the casing having a relatively fixed 75

5 piston chamber of elongated, substantially rectangular section extending lengthwise of the shaft, a piston fitting the chamber and two or more spaced pitman rods directly connected to the piston and the crankshaft.

10 3. In a pump or motor structure, a casing comprising oppositely disposed heads and an intermediate body section, the latter having walls extending between said heads and forming the relatively long side walls of rectangular piston chambers, the narrow side walls of which are formed by said heads, a crankshaft journaled in said heads, and pistons in said chambers connected to said shaft.

15 4. In a pump or motor structure, a shaft having two or more cranks, a plurality of piston chambers rectangular in section disposed in a circular series about the shaft with the relatively long side walls thereof extending lengthwise of the shaft, and pistons in said chambers, each connected to the multiple cranks of said shaft.

20 5. In a pump or motor structure, a casing comprising oppositely disposed heads and an intermediate substantially cylindrical body section, the latter having a circular series of rectangular piston chambers and intermediate jacketing spaces formed therein, the chambers being closed at their ends by said heads, a crankshaft journaled in said heads, pistons in said chambers, and a plurality of spaced pitman rods connecting each piston to said shaft.

25 6. In a pump or motor structure, a casing comprising a substantially cylindrical body, having formed therein a circular series of radial piston chambers of rectangular section open at the ends of the cylindrical body and intermediate jacketing spaces closed at their ends, heads secured to the opposite ends of said body and forming the ends of said piston chambers, a crankshaft journaled in said heads, and pistons in said chambers connected to said crankshaft.

30 7. In a structure of the class described, a casing comprising oppositely disposed heads and an intermediate body, the latter having a central crank chamber, a circular series of radial rectangular piston chambers closed at their relatively narrow ends by said heads, intermediate jacketing spaces and annular inlet and outlet manifolds, a crankshaft journaled in said heads and extending through said crank chamber, pistons in said piston chambers, and a pair of spaced pitman rods connecting each piston to said shaft.

35 8. In a compressor or engine structure, a series of radial pistons and piston chambers of enlarged rectangular section, a shaft having multiple cranks to which each of said pistons is connected, said shaft comprising multiple sections providing crank arms and pins and bolts extending through the crank pins and arms and rigidly connecting the shaft sections.

40 9. In a compressor or engine structure a series of radial pistons and piston chambers of enlarged rectangular section, a shaft having multiple cranks to which each of said pistons is connected, said shaft comprising multiple sections having integral crank arms, crank pins integral with certain of said arms and seated in recesses in the adjacent arms, and bolts extending through the crank arms and eccentrically through the crank pins for rigidly connecting said sections.

45 10. In a compressor or engine structure, a crankshaft, a series of radial pistons and piston

5 chambers of elongated rectangular section disposed about and lengthwise of the shaft, with each piston connected to a common crank or cranks thereof, and packing strips on the outer portions of the pistons and on the inner portions of the 5 walls of the piston chambers.

10 11. In a structure of the class described, a casing comprising oppositely disposed heads and an intermediate body, the latter having a central crank chamber and a circular series of radial rectangular piston chambers closed at their relatively narrow ends by said heads, and annular inlet and outlet manifolds, removable inlet and outlet valves and valve seats disposed in said manifolds at the outer ends of said piston chambers, a 15 crankshaft journaled in said heads and rectangular pistons in said chambers connected to the crankshaft.

15 12. In an elastic fluid pump or motor structure, rotor and stator members, one comprising a 20 crankshaft having aligned crank arms and the other a frame or casing having a crank chamber through which said crank extends and a plurality of piston chambers, said chambers in cross section being elongated lengthwise of the shaft and 25 substantially contracted transversely thereof, correspondingly shaped pistons in said chambers, and two spaced pitman rods connecting each piston to the aligned crank arms of said shaft.

20 13. In an elastic fluid pump or motor structure, 30 rotor and stator members, one comprising a crankshaft and the other a plurality of radial piston chambers having cross sections substantially elongated lengthwise of the shaft and contracted transversely thereof, correspondingly shaped pistons in said chambers, and two spaced pitman rods directly connected to each piston and the crankshaft.

25 14. In a structure of the class described, a casing comprising oppositely disposed heads and an 40 intermediate body, the latter having a central crank chamber and a circular series of radial, substantially rectangular piston chambers closed at their relatively narrow ends by said heads, a crankshaft journaled in said heads and extending 45 through the crank chamber, pistons fitting the piston chambers and connected to the crankshaft, and packing strips in the relatively long side walls of the piston chambers and in said heads and engaging the pistons.

30 15. An elastic fluid pump or motor structure comprising a casing, a crankshaft, the casing having a crank chamber and a radial series of piston chambers of substantially rectangular section elongated lengthwise of the shaft, correspondingly shaped pistons in said chambers, and two or more pitman rods connected directly to each piston and to the shaft, the rods being arranged in two or more sets and those of each set disposed substantially in a common plane.

35 16. An elastic fluid pump or motor structure comprising a casing, a crankshaft journaled therein, the casing having a crank chamber and a circular series of radial piston chambers substantially rectangular in section and elongated 65 lengthwise of the shaft, inlet and outlet manifolds, inlet and outlet valves connecting the manifolds with the outer end of each piston chamber, pistons in the chambers and a pair of spaced pitman rods connecting each piston with the crankshaft.
